UNITED STATES PATENT OFFICE.

FRANK E. COOK, OF TRAVERSE CITY, MICHIGAN, ASSIGNOR, BY MESNE ASSIGNMENTS, OF ONE-HALF TO THORNTON MITCHELL, OF TRAVERSE CITY, MICHIGAN.

BOAT AND PROPELLER MECHANISM.

No. 916,846.

Specification of Letters Patent. Patented March 30, 1909.

Application filed December 4, 1908. Serial No. 466,081.

To all whom it may concern:

Be it known that I, FRANK E. COOK, a citizen of the United States, residing at Traverse City, in the county of Grand Traverse and 5 State of Michigan, have invented certain new and useful Improvements in Boat and Propeller Mechanism; and I do hereby declare the following to be a full, clear, and exact description of the invention, such as 10 will enable others skilled in the art to which it appertains to make and use the same, reference being had to the accompanying drawings, and to the letters of reference marked thereon, which form a part of this 15 specification.

This invention relates to new and useful improvements in ships and mechanism for buoying the same to reduce the friction intermediate the outer surface of the boat and 20 the water, and comprises a peculiar shape of hull underneath which are positioned propeller wheels at such angles that, when driven through the water, they will have a tendency to raise the hull of the boat as well 25 as to impart a forward movement thereto. By the provision of my improved mechanism, an excessive speed may be obtained.

The invention comprises various details of construction, combinations and arrangements of parts which will be hereinafter 30 fully described and then specifically defined in the appended claim.

My invention is illustrated in the accompanying drawings, in which:—

35 Figure 1 is a side elevation of a boat constructed in accordance with my invention. Fig. 2 is a bottom plan view, and Fig. 3 is a cross sectional view.

Reference now being had to the details of 40 the drawings by letter, A designates the hull of a boat, a cross section of which is shown in Fig. 3, having a comparatively narrow keel B with flaring sides D. Positioned at the rear of the boat is the usual propeller E fixed 45 to the propeller shaft F and upon either side of the fin tail and slightly in advance of said propeller E, a shaft G projects through the hull of the boat at any suitable angle, preferably twenty-five degrees, and a propeller H is 50 fixed to each shaft G. Mounted amidships

on either side of the central keel are the similarly disposed shafts K seated at the same angle as the shafts G and fixed to each shaft K is a propeller wheel O. The hull of the boat adjacent to the location where the shafts 55 K project therethrough is recessed away as at N, the wall of which extends below the propeller O and affords means for protecting the blades thereof against any foreign matter which otherwise might come in contact 60 therewith. In Fig. 2, S designates diagonal engines, one being provided for driving each shaft.

In operation, the propellers upon the inclined shafts being driven of varying speeds 65 will have a tendency to raise the hull in the water at the same time of imparting a forward movement thereto and which forward movement is accelerated by a larger and main driving propeller E which is mounted 70 upon the horizontal shaft F. By the powerful movements imparted to the propeller shaft K, the widened portion of the hull of the boat will be seated so as to reduce to minimum the frictional contact of the surface 75 of the boat which comes in contact with the water, the faster the rotary movement imparted to the shafts K being tending to raise the boat and lessen the friction.

What I claim to be new is:—

In combination with the hull of a boat having a main propeller, propelling shafts positioned substantially at angles of twenty-five degrees to the perpendicular, one upon either side and slightly above said main propeller shaft and projecting underneath the fin tail of the boat, propellers upon said shafts, the hull of the boat being recessed away at opposite positions in advance of the transverse center of the hull, propeller shafts 85 projecting through the hull, one in each of said recesses and at angles of substantially twenty-five degrees to the perpendicular, substantially as shown and described.

In testimony whereof I hereunto affix my 90 signature in the presence of two witnesses.

FRANK E. COOK.
